UNITED STATES PATENT OFFICE.

ROWAN T. F. DODDS, OF STRATFORD, ONTARIO, CANADA.

METHOD OF PREVENTING EXPLOSIONS.

1,376,082.

Specification of Letters Patent. Patented Apr. 26, 1921.

Application filed May 10, 1920. Serial No. 380,203.

To all whom it may concern:

Be it known that I, ROWAN T. F. DODDS, a citizen of the United States, residing at Stratford, in the Province of Ontario, Dominion of Canada, have invented a new and useful Improvement in Methods of Preventing Explosions, of which the following is a full, clear, and exact description.

The present invention relates broadly to 10 humidifiers, but more particularly to a method of preventing the creation or existence of conditions conducive to explosions, by supplying water vapor to dust laden working areas as the dust therein absorbs 15 the available moisture from the atmosphere.

The principal object of the present invention is to maintain at all times in dust laden working areas a stable atmospheric condition tending to prevent explosions.

20 A further object of the present invention is to provide a method of maintaining predetermined minimum amounts of free water vapor in dangerous working areas.

Still a further object of the invention is 25 to localize in special instances the application of the additional water vapor whereby the desired conditions are maintained at the points of greatest danger.

The foregoing and other objects, together 30 with their attendant advantages, will be apparent as the invention becomes better understood by reference to the accompanying specification and drawing forming a part thereof, it being premised that changes may 35 be made in the various details and the manner of operation within the scope of the appended claims without departing from the spirit of the invention. In the drawings the figure is a diagrammatic illustration of 40 one form of apparatus suitable for carrying out my invention.

At the present time there is annually a great loss of life and property due to explosions occurring in coal mines, flour and 45 feed mills, grain elevators, threshing machines, separators and the like. These explosions are universally attributed to the existence in the atmosphere of amounts of dust or powder in such proportions that an 50 explosive mixture is produced. The actual explosion of such mixtures has been brought about in various ways as by the production of sparks, heat, flames or concussions. Heretofore efforts to prevent such explosions 55 have been directed toward the elimination

either of the dust or powder from the atmosphere, or of the means responsible for the production of the explosion. These efforts have not overcome the danger inherent in industries in which these conditions exist and the present invention is directed, not toward the elimination either of the explosive material in the atmosphere, or of the means which bring about the explosion, but toward the prevention of an atmospheric 60 condition capable of supporting combustion or of permitting explosions.

By a series of experiments and investigations extending over a number of years, I have found that the dust or powder present 70 in the atmosphere possesses deliquescent properties and that therefore where they are present in sufficient quantities, and where the supply of fresh air is limited, they absorb all of the available moisture in the air with- 75 in a predetermined working area and thereby produce an unstable atmospheric condition. As air under the common designation is composed of a large number of different independent elements combined in mechan- 80 ical relationship, the elimination of the water vapor produces an unstable relation- 85 ship between the remaining constituents and explosions may be produced by any one of a large number of independent disturbances. 85 The present invention aims to prevent the creation or existence of such unstable relationship by maintaining at all times a pre- 90 determined minimum of water vapor in the atmosphere by supplying additional water vapor as the free vapor is absorbed by the dust.

In the figure of the drawings there is illus- 95 trated a form of apparatus capable of preventing explosions in grain elevators or bins. As illustrated, this apparatus comprises a tank 1 of any desired construction, having a water inlet 2 controlled by a float 3 or similar device for maintaining a predetermined water level within the tank. Extending be- 100 low the water level therein is a perforated pipe 4 which is connected to a fan or other blower 5 for forcing air therethrough. This air escaping through the perforations in the pipe 4 will pick up a large amount of mois- 105 ture and this moisture laden air may be conducted through a suitable pipe 6 to a moisture conductor 7 extending within the ele- 110 vator or bin 8, to a point adjacent the bottom thereof. This conductor may be pro-

vided with a series of openings 9 gradually increasing in size toward the bottom of the elevator or bin. By reason of this construction it will be apparent that if the bin is 5 empty and grain is fed thereinto with the blower 5 in operation, moist air will be directed into the interior of the bin. The major portion of this air will be directed inwardly into that portion of the working 10 area which is receiving the grain due to the provision of the largest escape openings at such point. As the grain gradually fills the bin these openings will be gradually covered and the point of application of the moist air 15 will be gradually raised. During the entire filling operation, however, moist air will be supplied directly into that working area in which an explosion is most apt to occur. This will result in preventing the creation 20 of an atmospheric condition rendered unstable by the elimination of water vapor, thereby negating the possibility of an explosion.

It will be apparent that this invention 25 may be applied in any desired manner in connection with any of the dangerous industries of the character specified herein. By the term "dust" or "powder", as employed throughout this specification and 30 claims, there is meant any material which combined in proper quantities with the air will produce an explosive mixture.

It has been observed that the possibility 35 of explosions is increased in dealing with grains as these substances contain large amounts of mineral matters. My invention, therefore, as described in connection with grain bins and elevators, is particularly valuable although this application is 40 not limited in this respect.

The advantages of the present invention arise from the method for preventing the creation or existence of an atmospheric condition conducive to explosions.

45 Further advantages of the invention arise from the method of directing the moist air directly into the working area possessing the most dangerous characteristics.

I claim:

50 1. The method of preventing explosions in dust laden working areas, comprising supplying additional water vapor to the area as the free vapor therein is absorbed by the dust, to maintain an effective stabilizing 55 minimum of moisture at all times, substantially as described.

2. The method of preventing explosions

in dust laden working areas, comprising supplying additional water vapors locally into the most dangerous portions of said 60 areas as the free vapor therein is absorbed by the dust, to maintain an effective stabilizing minimum moisture at all times, substantially as described.

3. The method of preventing explosions 65 in handling material, comprising supplying water vapor to said material during the handling thereof, to prevent the creation of an unstable atmospheric condition by maintaining an effective stabilizing mini- 70 mum of moisture at all times, substantially as described.

4. The method of preventing explosions in grain elevators, comprising supplying water vapor to the interior of said elevators 75 during the handling of the material therein as the material absorbs the available moisture, to maintain an effective stabilizing minimum of moisture at all times, substantially as described.

5. The method of preventing explosions 80 in grain elevators, comprising supplying additional water vapor to the interior of said elevators during the filling thereof, said water vapor being supplied at progressively higher levels as the bins become 85 filled, to maintain an effective stabilizing minimum of moisture therein at all times, substantially as described.

6. The method of preventing explosions 90 in grain elevators, comprising supplying additional water vapor to the interior of said elevators during the filling thereof, said water vapor being automatically supplied at progressively higher levels as the 95 bins become filled, to maintain an effective stabilizing minimum of moisture therein at all times, substantially as described.

7. The method of preventing explosions 100 in working areas laden with deliquescent dust, comprising the maintenance of a stabilized atmospheric condition by the addition of water vapor to the area as the free vapor therein is absorbed by the dust, substantially as described.

8. The method of preventing explosions 105 in dust laden working areas, comprising the production of moist air, and then supplying said air to the area as the free vapor therein is absorbed by the dust, substantially as described.

In testimony whereof, I have hereunto set my hand.

ROWAN T. F. DODDS.
